(57) **CLAIM**

The ornamental design for an ultra-thin solar module, as shown and described.

DESCRIPTION

FIG. 1 is a perspective view of an ultra-thin solar module showing my new design;

FIG. 2 is a perspective view thereof from another angle;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is an enlarged view of a portion indicated with numeric 9 in FIG. 1;

FIG. 10 is an enlarged view of a portion indicated with numeric 10 in FIG. 2; and,

FIG. 11 is a perspective view thereof when the solar module is detached from the base.

The broken lines shown indicate the boundaries of the enlarged views and form no part of the claimed design.
